UNITED STATES PATENT OFFICE

JOSEPH W. THOMPSON, OF SALEM, OHIO, ASSIGNOR OF ONE-HALF TO THE
BUCKEYE ENGINE COMPANY, OF SAME PLACE.

WIRE-NAIL MACHINE.

SPECIFICATION forming part of Letters Patent No. 445,097, dated January 20, 1891.

Application filed September 6, 1890. Serial No. 364,136. (No model.)

To all whom it may concern:

Be it known that I, JOSEPH W. THOMPSON, of Salem, in the county of Columbiana and State of Ohio, have invented certain new and useful Improvements in Wire-Nail Machines, 5 of which improvements the following is a specification.

My present invention relates to and is an improvement upon certain features of wire-nail machines of the type of that for which Letters Patent of the United States No. 398,009 were granted and issued unto myself and the Buckeye Engine Company, as assignee of half the right, under date of February 19, 15 1889.

The objects of my invention are as follows: first, to more perfectly adapt the machine to smooth and quiet operation at high speed by the provision of improved means for effecting the preliminary closure of the gripping-dies with sufficient force to hold the wire against the backward movement of the feed-carriage, and to properly center the wire to be acted on by the cutting-knives, the secondary grip, by which the wire is held with the requisite force during the heading operation, being subsequently effected by pressure derived from the heading-crank; second, to attain greater convenience and facility in the adjustment of the cutters both toward and from the gripping-dies for the purpose of varying as required the amount of "stock" allowed to project from the dies to form the head, and also in the vertical adjustment of the cutters in order that they may meet each other and the wire fairly and centrally; third, to insure positive release of the wire by the feeding mechanism during the backward movement of the feed-carriage, and thereby to avoid the objections resultant upon the backward dragging of the feed-chisel along the wire—that is to say, the scraping and marring of the body of the nail, the accumulation of cuttings due to such scraping, and the rapid dulling of the feed-chisel; fourth, to attain greater facility and convenience in the manipulation and adjustment of the straightening-rollers.

To these ends my improvements consist in

certain novel devices and combinations of 50 mechanism hereinafter fully set forth.

In the accompanying drawings, Figure 1 is a vertical longitudinal central section through a wire-nail machine embodying my invention; Fig. 2, a plan or top view of the same; Fig. 3, an end view in elevation, as seen from the right; Fig. 4, a horizontal section at the line $x-x$ of Fig. 1; Fig. 5, a similar section at the line $y-y$ of Fig. 1, through the portion of the frame to which the pivots of the cutting-levers are secured; Fig. 6, a view in elevation of one of the pins to which the cutting-levers are pivoted, and of the section of the divided eccentric block in which said pin is fitted; Fig. 7, a view in perspective of one of the 65 divided eccentric blocks; Fig. 8, a vertical longitudinal central section through the lower portion of the machine, illustrating a modification of the gripping mechanism; Fig. 9, a vertical longitudinal section through the gripping mechanism of Fig. 1, showing the parts in the positions occupied during the secondary grip of the wire for the heading operation, they being shown in Fig. 1 at the commencement of the gripping movement; Fig. 70 10, a similar section illustrating another modification of detail of the gripping mechanism; Figs. 11 and 12, vertical sections through the straightening mechanism showing the rollers as released from and pressed against the wire, 75 respectively; Fig. 13, a partial plan view of the same; and Fig. 14, detail views of the device for effecting positive release of the grip of the feeding mechanism.

The machine herein illustrated accords in 85 its general and essential features of operation with that set forth in Letters Patent No. 398,009 aforesaid—that is to say, in the consecutive and continuous performance of the straightening and the feeding of a length of 90 wire between gripping-dies for a distance sufficient to form a nail, the gripping of the wire by said dies, the cutting off and pointing of the nail, the heading of the projecting portion of wire for the nail, and the release and 95 delivery of the finished nail. The structural elements of the machine by which these operations are effected and their co-operative

relation will now be at length and in detail described.

The operative mechanism is, as in Patent No. 398,009, mounted and supported upon a frame composed of a horizontal table or bed 1 and vertical standards or legs 2, and a driving-shaft 3, carrying fast and loose pulleys 3^b 3^c for the reception of a belt, through which the operating-power is transmitted from a suitable prime mover, is mounted in bearings 1^a on the table 1. A double crank 3^a is formed upon the shaft 3, said crank actuating the cutting and pointing and heading mechanisms and effecting the secondary grip or closure of the gripping-dies through connections hereinafter described, and the shaft 3 carries upon one of its ends a crank disk or arm 3^d for operating the mechanism by which the wire is progressively fed or advanced to be formed by cutting and heading into a series of nails. A cam 3^e is also fixed upon the shaft 3 adjacent to the crank 3^a, said cam serving to effect through interposed connections the preliminary closure of the gripping-dies upon the wire, by which the latter is held while being cut off and during the retraction of the feed-carriage.

The straightening mechanism, by which the length of wire is properly aligned preparatory to being subjected to the remaining operations involved in its conversion into finished nails, is shown fully in Figs. 2, 11, 12, and 13, and consists of a series of peripherally-grooved rollers 34, journaled in line on spindles 35, fixed to the table of the machine adjacent to its left-hand or receiving end at a proper height to receive the wire 28 to be operated on in their peripheral grooves as the wire passes to the feeding mechanism, and two or more rollers 36, which are journaled in the same horizontal plane as the rollers 34 upon the laterally-expanded head of a tubular carrier 37, which is fitted to slide longitudinally upon a stem 38 toward and from the relatively fixed rollers 34. The end of the stem 38 adjacent to the rollers 34 is provided with a T-shaped head 40, and is pivoted to the table by a bolt 39, about the axis of which the stem 38 and carrier 37 have a limited range of traverse in a horizontal plane, being adjusted and held in the desired angular relation to the axial line of the wire by set-screws 41, engaging threaded lugs 42 on the table and abutting against the arms 55 of the T-head 40 of the stem 38. A tubular nut 43, through which the stem 38 passes freely, is screwed into the outer or free end of the carrier 37, and a helical spring 44 is interposed between the inner face of the nut 43 and a shoulder on the stem 38, the tension of said spring acting to force the carrier 37 and rollers 36 away from the relatively fixed rollers 34. A lever-handle 45 is pivoted to the outer end of the stem 38 with the capacity of being swung into either a vertical or a horizontal position, as shown in Figs. 11

and 12, respectively. The relative distances of the side and end of the shorter arm of the lever-handle 45 from the pivot thereof are such that when in vertical position the latter permits the spring 44 to force the carrier 37 and rollers 36 sufficiently far from the rollers 34 to permit the wire to pass freely and without contact between the rollers 34 and 36 but when turned into horizontal position it compresses the spring 44 and forces the carrier 37 and rollers 36 toward the rollers 34, thereby bringing said rollers into sufficient proximity to cause the wire to be bent to a more or less sinuous course as it passes between the rollers, such bending being greater or less in degree accordingly as the nut 43 is screwed a less or greater distance into the carrier 37. When it is desired that the rollers 36 shall bear with equal force upon the wire, the set-screws 41 are adjusted so as to place the stem 38 and carrier 37 at right angles to the line of traverse of the wire, as shown in Fig. 2, and when it is desired that the several rollers 36 shall bear unequally upon the wire one of the set-screws 41 is slackened and the other tightened, so as to bring the stem and carrier to the inclination proper to effect the unequal bearing desired, as shown in Fig. 13.

The method of straightening wire by alternately bending it in opposite directions from its line of traverse is familiar to those skilled in the art, and is conveniently carried out by the construction above described.

The feeding mechanism is of the following construction: The feed-carriage 20 is fitted to be reciprocated between dovetailed guides 21, formed integral with the table 1 on one side and gib-plates 21^a on the other, said plates being bolted in position and adjusted and held by set-screws 21^b. Longitudinal reciprocation on the table is imparted to the carriage 20 by a connecting-rod 22, which is coupled at one end to a crank-pin 23 on the crank or disk 3^d, and is secured at the other to a shaft 24, journaled in a transverse bearing on the feed-carriage 20. The crank-pin 23 is secured adjustably in a radial groove or slot in the disk 3^d, so that the traverse of the feed-carriage may be increased or diminished as required, for different lengths of nails, and as the driving-shaft 3 rotates in the direction of the arrow the connecting-rod 22 will be raised above its mean position while the feed-carriage is moving backward, and will be depressed below its mean position as the carriage moves forward in feeding the wire. By the term "forward," as applied herein to the movements both of the feed-carriage and of the heading-ram, is meant the direction of traverse in which the work of the respective members is performed, which directions are relatively opposite one to the other. A collar 24^a is secured upon the end of the shaft 24 which is farthest from the connecting-rod 22, said collar being provided

with a projecting arm or lug 24^b. A double-armed feed-dog 25, carrying on its inner and shorter arm a rod 27, having a chisel-faced end which bites into and draws the wire 28 along when the carriage is moved forward, is pivoted on a stem 26, located on the feed-carriage in such position that its longer arm may be pressed against by a spring 29 with sufficient force to insure a proper bite of the feed-chisel 27 on the opposite arm of the dog, upon the wire which passes between the feeding end of said chisel and a bearing 30, secured adjustably upon the carriage opposite thereto. It will be seen that oscillatory movement will be imparted to the shaft 24 and collar 24^a by reason of the vertical movement of the connecting-rod 22, as actuated by a crank-pin moving in a circular path, and in the oscillation of the shaft 24 during the backward traverse of the carriage the lug 24^b will bear against the adjacent arm of the dog 25, and, overcoming the tension of the spring 29, will withdraw the end of the feed-chisel 27 from the wire. When the adjustments are properly made, the contact of the lug 24^b with the dog 25 will take place when the crank-pin 23 is on its outer dead-center—that is to say, when the feed-carriage has just completed its forward movement—and the lug will hold the feed-chisel clear of the wire during the entire backward movement of the feed-carriage, allowing it to be again brought into contact with the wire by the spring 29 at the opposite dead-center and during the succeeding forward movement of the feed-carriage. To provide for effecting the adjustments requisite to accomplish the above result, the end of the shaft 24, on which the connecting-rod 22 is fitted, is made of somewhat greater diameter than the remainder of the shaft, and is recessed to afford bearings on opposite sides of its center for two set-screws 24^c 24^d, each of which will when tightened tend to rotate the shaft 24 in one direction with relation to the connecting-rod, the rotating action of the two set-screws being relatively opposite. When both set-screws are tightened, or either alone, the connecting-rod is firmly locked to the shaft, and when one set-screw is slackened and the other tightened the shaft will be correspondingly rotated. When it is found that the feed-chisel fails to come in contact with the wire soon enough and moves out of contact with the wire too soon, the adjustment requisite to correct such imperfect action may be made by slackening the lower set-screw 24^d and tightening the upper one 24^c.

The wire 28 is preliminarily gripped or held stationary during the cutting and pointing operation, and secondarily gripped with greater force during the heading operation by mechanism which will now be described. The gripping-dies 18 18^a, between which the wire is held, are, as in Patent No. 298,009, respectively, fixed and movable in a vertical die-block 16, secured to the table 1, the lower movable die 18^a being, in my present inven-

tion, preliminarily moved toward the upper fixed die 18 by means of the cam 3^e, and being secondarily moved more closely toward the fixed die by a right-angled lever-connecting block 5, coupled to the pin or the crank 3^e, said block so far according with that of Patent 398,009 that my present invention may be clearly understood by a description of the intermediate mechanism, through which it actuates the movable die without herein setting forth in detail its specific construction and operative principle. A transverse rock-shaft 13 is journaled in bearings on the frame of the machine below the driving-shaft 3, the shaft 13 having an upwardly-projecting arm 13^a, secured upon one of its ends, upon which arm is journaled a roller 13^c, the periphery of which abuts against the face of the cam 3^e of the driving-shaft. A downwardly-projecting arm 13^b is secured upon the rock-shaft 13 in or near the vertical central plane of the machine, said arm having a horizontal spreader-bar 13^d coupled to its lower end. The opposite or forward end of the spreader-bar is provided with an enlarged head 13^e, the outer faces of which are curved or inclined above and below its center, so as to be capable of exerting a wedging action, and the head has substantially parallel upper and lower faces for the remainder of its length. The wedging-faces of the head 13^e are adapted to pass between and bear on the peripheries of two rollers 15^b and 14^b, one of which 15^b is journaled in the free end of a gripping-lever 15, which is pivoted by a pin 15^a to a bracket bolted to the frame below the die-block 16, and the other 14^b is similarly mounted on an intermediate lever 14, journaled on the frame below and near the outer end of the gripping-lever 15. A vertical bolt 15^c engages a thread in the gripping-lever near its pivot, the upper rounded end of which bolt enters a socket in the lower end of a push-bar 15^d, having a rounded upper end, which enters a corresponding socket in the lower end of the movable gripping-die 18^a. A pull-rod 19 is hooked at its upper end into the die 18^a and is connected at its lower end to the gripping-lever 15, the pull-rod acting to depress the movable die 18^a to release the wire upon the downward movement of the gripping-lever, as in Patent No. 398,009.

The free end of the intermediate lever 14 is coupled by a link or links 14^a (the connecting-pins of which may be fitted in either of a series of holes in the lever 14 to enable its traverse to be varied) to an arm 6^b, fixed upon a shaft 6^a, which is journaled in the frame above the spreader-bar and has secured upon it one or more radius-bars or links 6, which are coupled at their upper ends to the pin 5^e, which connects the heading-ram 4 to the right-angled lever-connecting block 5. A spring or pair of springs 13^h, connected to the frame, bear against a pin on the spreader-bar 13^d, tending to force the same away from the rollers 15^b and 14^b.

The operation of the gripping mechanism will be readily understood by reference to Figs. 1 and 9, the former showing the position of the parts at the beginning of the preliminary grip or closure of the gripping-dies while the nail is being cut off, and the latter in the secondary and more forcible grip which the dies exert upon the wire during the heading operation. The configuration of the cam 3^e is such that at the proper period in the rotation of the driving-shaft (being shortly after the commencement of the forward movement of the heading-ram) the cam 3^e forces the upperarm 13^a of the rock-shaft 13 to the right, coincidently moving the lower arm 13^b and the spreader-bar 13^d in the opposite direction and forcing the wedging-faces of the head 13^e of the spreader-bar between the rollers 14^b and 15^b. The intermediate lever 14 and roller 14^b being at this period held unyieldingly by the connection of the lever 14 with the connecting-block 5, the roller 15^b and gripping-lever 15 are lifted, and the gripping-lever, acting on the movable die 18^a, through the bolt 15^c and push-bar 15^d, closes the dies on the wire 28, effecting their preliminary grip, the force of which is sufficient to center and hold the wire while being cut off by the cutting-knives and while the backward traverse of the feed-carriage is being effected. As the heading-ram 4 moves forward toward the stub of wire projecting from the dies to form the head of the next nail, the block 5, through the links 6, arm 6^b, and links 14^a, lifts the intermediate lever 14, which in turn lifts the spreader-bar 13^d, raising the roller 15^b and gripping-lever 15 a sufficient distance to effect the secondary and more forcible grip of the dies upon the wire, by which the wire is securely held against being driven backward by the pressure of the ram in forming the head. Upon the relief of the pressure of the cam 3^e on the roller 13^b at the termination of the heading operation, the spring 13^b forces the spreader-bar away from the rollers 14^b and 15^b and the gripping-lever 15 falls by gravity, opening the dies and admitting of the requisite forward feed of the wire for the next operation. A spring exerting downward tension upon the gripping-lever 15 may, if desired, be applied to insure its proper downward movement.

It will be seen that as the parallel sides of the head of the spreader-bar are in contact with the rollers 14^b and 15^b during the secondary grip of the dies the additional gripping-pressure does not impose any additional stress upon the cam 3^e, and as the dies need be, and in practice are, closed with only moderate force in the preliminary grip, the pressure on the cam is at no time undue or severe. In nail-machines of the ordinary construction the gripping-cam acts either directly upon a roller mounted on the gripping-lever or on a lever coupled thereto, so that the pressure of the roller on the cam is at all times proportionate to the gripping force, and

cams so operating therefore require to be made of the hardest material available, notwithstanding the use of which they are found to rapidly wear out.

The duty imposed on the cam and roller of my improved construction is so light that the cam may be made of ordinary iron without being subject to unduly rapid wear.

Fig. 10 illustrates a modification in detail of the gripping mechanism above described, in which the traverse of the spreader-bar and the inclination of the wedging-faces of its head are in opposite direction to the same features as above described, the arm 13^a and 13^b being located on the opposite side of the cam 3^e. This arrangement may be found desirable in the respect that the stress which it imposes on the driving-shaft is in the same direction as that imposed by the heading-ram when forming the head of the nail.

The further modification of the gripping mechanism shown in Fig. 8, may be adopted in cases where the size, proportions, and duty of the machine render it advisable. In this instance the intermediate lever 14 and its connections 14^a are dispensed with, and the roller 14^b is mounted directly on the arm 6^b, or between two of said arms, the shaft 6^a of said arm, which in this case performs the function of and acts as the equivalent of the intermediate lever 14, being journaled below the gripping-lever instead of above it, as in the former instances. In all other structural and operative particulars the construction accords with that of Figs. 1 and 9. Such modification embodies the advantages of simplicity and cheapness, but does not provide for the convenient variation of the secondary grip movement that may be required to adapt the machine for operation on wire of different diameters, as the smaller the wire operated on the less is the secondary grip movement required.

The cutting and pointing mechanism is, in its general features, similar to that of Patent No. 398,009—that is to say, the cutting and pointing is effected by a pair of cutters 12^b, connected to the free ends of a pair of cutting-levers 12, which are pivoted vertically to the table and are coupled by links 11 to the upper arms 10^a of a pair of vertical rock-shafts 10, the lower arms 9 of which are coupled by a pair of connecting-rods 8 to a pin 5^b on the lower or vertical arm of the connecting-block 5. The improved adjustment of the cutting-knives to which this branch of my present invention relates is attained by the following means:

Each of the cutting-levers 12 is journaled on a stud or pin 12^a, secured upon a divided eccentric block 12^c, which is fitted, with the capacity of rotation, in a circular orifice in the table 1 of the machine, and is provided with an upper flange 12^d, which rests upon the top of the table and retains the eccentric in proper position vertically. The studs 12^a are threaded on their lower ends and engage

corresponding female threads in the eccentric blocks 12^c , one-half of the receiving-threads being cut in each section of the eccentric blocks, and the two sections being cut away slightly 5 on the surfaces adjoining the receiving-thread, so as to close tightly on the threaded end of the stud without coming in contact one with the other. A recess 12^e is formed in each section of the eccentric blocks, said recesses serving for the reception of set-screws 12^f 12^g , (one for each section,) which set-screws engage female threads in the table and bear against the substantially radial faces of the recesses 12^e . The eccentric blocks may be 10 turned in either direction, as desired, in the openings of the frame in which they are fitted, and fixed in adjusted position therein by slackening one set-screw and tightening the other, the pressure of the respective set-screws of each pair, when one is unopposed by the other, acting to turn the eccentric block in one or the other direction, respectively, and the coincident pressure of both set-screws acting to clamp the eccentric block firmly 15 upon the stud and hold the block in any position to which it may be brought.

The bearing-studs 12^a of the cutting-levers 12 being connected eccentrically to the eccentric blocks 12^c , rotation of the blocks will 20 increase or diminish the distance of the studs from the gripping-dies, and thereby cause the wire to be cut off at a greater or less distance from the dies, leaving a correspondingly greater or less length of stock for 25 the formation of the head of the nail. The slackening of the screws 12^f and tightening of the screws 12^g will increase the length of stock, and vice versa. The vertical adjustment of either of the cutting-levers is effected 30 by slackening one of the set-screws of the eccentric block sufficiently to permit the stud to be turned in its threaded bearing in the block, so as to raise or lower it, and with it the cutting-lever which it carries, as far as 35 desired. When brought to proper position, the set-screw is again tightened and the stud firmly held in place. Squared or hexagonal heads may be formed upon the studs to admit of the application of a wrench in making 40 the above adjustments.

Instead of being entirely divided, as above described and shown, the eccentric blocks may be cut only partially across, so as to be sprung upon the studs 12^c , or an undivided 45 eccentric may, if preferred, be employed, the stud being in such case either connected permanently thereto and the vertical adjustment being effected by the coincident elevation or depression of the block and stud, or 50 being connected frictionally to the block and independently vertically adjusted.

The heading of the nail is effected by a heading-punch 4^a , secured in a heading-ram 4 , which is coupled by a pin 5^e to the outer 55 end of the upper end of the outer or horizontal arm of the connecting-block 5 . The heading mechanism is substantially similar

in construction and operation to that of Patent No. 398,009, and as it does not in and of itself embody features of my present invention it need not be herein at length described. 70

I have herein exemplified that portion of my present invention which relates particularly to the gripping mechanism as embodied and applied in a machine in which a single 75 crank-pin upon the driving-shaft actuates, through the intermediation of a connecting-block of the special construction set forth in Patent No. 398,009 aforesaid, and not herein claimed, both the heading-ram and the cutting mechanism, the features of improvement in the gripping mechanism claimed as of my present invention being desirably adaptable to and capable of full and clear illustration in a machine of such construction. It will, 80 however, be obvious that the employment of the specific form of connecting-block herein shown—*i. e.*, a right-angled lever connecting-block having an arm additional and supplemental to that which actuates the heading-ram and provided for effecting a separate function—while proper in is not essential to the practice of my present invention, and that so far as the improvement in the gripping mechanism thereof is concerned the same would 85 be applicable without substantial variation either of structure or operation in a machine in which the heading-ram and the cutting mechanism were operated through separate and independent connections from the driving-shaft, or in which a separate connection having a movement substantially coincident with that of the forward movement of the heading-ram is employed to transmit pressure for effecting the secondary grip to the movable 90 die. I do not, therefore, limit my present invention to a construction which embodies the specific connecting-block herein shown, and by the term "connecting-block" as used in the claims I include as a mechanical equivalent a rod or bar of the form known in the art by which a heading-ram is coupled to and its reciprocation effected by a crank-pin on the driving-shaft. 95

I claim as my invention and desire to secure 100 by Letters Patent—

1. In a wire-nail machine, the combination of a driving-shaft, a cam fixed therein, a heading-ram actuated by the driving-shaft, and a gripping-die actuated by suitable known mechanical connections, to which movement is imparted, preliminarily from the cam and secondarily from the driving-shaft, in substantial coincidence with the movement of the heading-ram, substantially as set forth. 110

2. In a wire-nail machine, the combination of a driving-shaft, a cam fixed thereon, a heading-ram actuated by the driving-shaft, a fixed gripping-die, a movable gripping-die, a gripping-lever coupled to the movable die, an intermediate lever coupled to and vibrated by the driving-shaft in substantial coincidence with the movement of the heading-ram, and a spreader-bar actuated by the cam and 120

- adapted to preliminarily transmit pressure from the cam to the gripping-lever and secondarily transmit increased pressure from the driving-shaft to said lever through connections independent of the cam, substantially as set forth.
3. In a wire-nail machine, the combination of a driving-shaft, a cam fixed thereon, a heading-ram actuated by the driving-shaft, a fixed gripping-die, a movable gripping-die, a gripping-lever coupled to the movable die, an intermediate lever coupled to and vibrated by the driving-shaft in substantial coincidence with the movement of the heading-ram, a spreader-bar actuated by the cam and adapted to preliminarily transmit pressure from the cam to the gripping-lever and secondarily transmit increased pressure from the driving-shaft to said lever through connections independent of the cam, and a spring acting upon the spreader-bar in opposite direction to the pressure imparted thereto by the cam, substantially as set forth.
4. In a wire-nail machine, the combination of a driving-shaft, a cam fixed thereon, a heading-ram actuated by the driving-shaft, a fixed gripping-die, a movable gripping-die, a gripping-lever coupled to the movable die, an intermediate lever coupled to and vibrated by the driving-shaft in substantial coincidence with the movement of the heading-ram, a spreader-bar actuated by the cam and provided with an enlarged and wedge-faced head adapted to be forced between bearings on the gripping-lever and the intermediate lever by pressure from the cam, and a spring acting upon the spreader-bar in opposite direction to the pressure imparted thereto by the cam, substantially as set forth.
5. In a wire-nail machine, the combination of a driving-shaft, a cam fixed thereon, a heading-ram, a connecting-block coupled to a crank-pin on the driving-shaft and to the heading-ram, a fixed gripping-die, a movable gripping-die, a gripping-lever coupled to the movable die, a roller journaled on said gripping-lever, an intermediate lever coupled to and vibrated by the connecting-block, a roller journaled on said intermediate lever, a double-armed rock-shaft having a roller on its upper arm bearing on the periphery of the cam, a spreader-bar connected to the lower arm of the rock-shaft and provided with an enlarged and wedge-faced head adapted to be forced between the rollers of the gripping and intermediate levers by the pressure of the cam on the roller of the rock-shaft arm, and a spring acting upon the spreader-bar in opposite direction to the pressure imparted thereto by the cam, substantially as set forth.
6. In a wire-nail machine, the combination of a bearing-block fitted with the capacity of axial adjustment in the frame of the machine, and a cutting-lever journaled eccentrically on said bearing-block, substantially as set forth.
7. In a wire-nail machine, the combination

of a bearing-block fitted with the capacity of axial adjustment in the frame of the machine and provided with opposite lateral recesses, 70 adjusting-screws, each bearing against the frame and against the face of one of said recesses, and a cutting-lever journaled eccentrically on the bearing-block, substantially as set forth.

8. In a wire-nail machine, the combination of a bearing-block fitted with the capacity of axial adjustment in the frame of the machine, said block being provided with a threaded opening eccentric to its axis and 80 being split or divided radially on opposite sides of said opening, adjusting-screws bearing against the frame and against opposite lateral faces on the bearing-block, a cutting-lever pivot having a thread engaging that of 85 the opening of the block, and a cutting-lever journaled on said pivot, substantially as set forth.

9. In a wire-nail machine, the combination of a driving-shaft, a fixed gripping-die, a 90 movable gripping-die actuated through intermediate connections from the driving-shaft, a bearing-block fitted with the capacity of axial adjustment in the frame of the machine, and a cutting-lever journaled eccentrically on said bearing-block, so as to be brought nearer to or farther from the gripping-dies by axial adjustments of the bearing-block, substantially as set forth.

10. In a wire-nail machine, the combination of a driving-shaft, a feed-carriage fitted to reciprocate on the frame of the machine, a connecting-rod coupled to a crank-pin rotated by the driving-shaft and to the feed-carriage, a double-armed feed-dog pivoted on 105 the feed-carriage and having an arm which is moved in opposite directions by the vertical vibration of the connecting-rod and by a spring, respectively, and a feed-chisel fixed to the opposite arm of the feed-dog, substantially as set forth.

11. In a wire-nail machine, the combination of a driving-shaft, a feed-carriage fitted to reciprocate on the frame of the machine, a shaft journaled transversely on the carriage, a connecting-rod secured to said shaft and coupled at its opposite end to a crank-pin rotated by the driving-shaft, a double-armed feed-dog pivoted on the feed-carriage, a lug fixed to the transverse shaft of the carriage and bearing against one of the arms of the feed-dog, a spring exerting tension upon the feed-dog in direction opposite to that of the pressure of the lug, and a feed-chisel fixed to the opposite arm of the feed-dog, substantially as set forth.

12. In a wire-nail machine, the combination of a series of straightening-rollers journaled upon pivots fixed to the frame of the machine, a stem pivoted to the frame adjacent to said rollers, a carrier fitted to move longitudinally upon said stem, and straightening-rollers journaled upon pivots fixed to said carrier, substantially as set forth.

13. In a wire-nail machine, the combination of a series of straightening-rollers journaled upon pivots fixed to the frame of the machine, a stem having a laterally-enlarged head and pivoted to the frame adjacent to said rollers, a carrier fitted to move longitudinally upon the stem, straightening-rollers journaled on pivots fixed to the carrier, a spring bearing against the stem and against the carrier, a lever pivoted to the stem and

adapted to bear against the carrier in direction opposite to that of the tension of the spring, and adjusting-screws bearing against the frame and against the lateral enlargements of the head on the stem, substantially 15 as set forth.

JOSEPH W. THOMPSON.
